CLAIM

The ornamental design for the light fixture, as shown and described.

DESCRIPTION

FIG. 1 is a perspective view of a first embodiment of a light fixture of the present invention; and

FIG. 2 is a front view thereof; and

FIG. 3 is a rear view thereof; and

FIG. 4 is a left side view thereof; and

FIG. 5 is right side view thereof; and

FIG. 6 is a bottom view thereof; and

FIG. 7 is a perspective view of a second embodiment of the light fixture of the present invention; and

FIG. 8 is a front view thereof; and

FIG. 9 is a rear view thereof; and

FIG. 10 is a left side view thereof; and

FIG. 11 is a right side view thereof; and

FIG. 12 is a bottom view thereof; and

FIG. 13 is a perspective view of a third embodiment of the light fixture of the present invention; and

FIG. 14 is a front view thereof; and

FIG. 15 is a rear view thereof; and

FIG. 16 is a left side view thereof; and

FIG. 17 is a right side view thereof; and,

FIG. 18 is a bottom view thereof.

Wherein the dotted lines herein show elements of the present invention that do not form part of the claimed design.
